UNITED STATES PATENT OFFICE

FREDERICK B. CUMPSTON, OF BLOOMING GROVE, TEXAS, ASSIGNOR TO ASSOCIATED FACTORIES CORPORATION, OF DALLAS, TEXAS, A CORPORATION OF DELAWARE
COTTON-GIN MACHINERY

Application filed September 16, 1929. Serial No. 392,914.

This invention relates to cotton gin machinery, and the primary object thereof is to provide a new arrangement of parts whereby the customary saw gin ribs of such machines are dispensed with.

In a former application for Letters Patent of the United States, filed by the applicant herein, there was disclosed a working embodiment illustrating the same principle involved in this present application.

Applicant now seeks to improve certain parts in a cotton gin construction as referred to above, whereby, in addition to the eradication of the regular gin rib construction, there are provided a multiple series of saws disposed on an inclined plane. Operably associated with the saws are certain other cooperating parts, including principally a stripper, and conveying means to carry away the lint and seed, the latter means being in common use in machines of this sort.

The combined result is an increase in capacity and in general utility in a cotton gin of the class hereinbefore referred to.

The invention will be more clearly and readily understood from a perusal of the following detailed description, taken in connection with the accompanying drawings, and wherein:

Figure 1 is a sectional view of a cotton gin, illustrating the improved gin.

Figure 2 is a detail sectional view of a saw assembly, illustrating their mode of disposal on a shaft.

Figure 3 represents a side elevational view of a spiked roller shaft, one of which is disposed between each series of saws, and

Figure 4 is a fragmentary detail perspective view of a stripper.

Having a more detailed reference to the drawings, 1 denotes a housing or casing, including a base 2 and rear walls 2', enclosing the gin mechanism. It should be here understood, in this connection, that the gin embodying the principle involved, is capable of both the ginning and of the reginning of cotton.

Inside the housing is an inclined supporting means in the form of beams 3, but any other suitable construction in this respect

may be employed that will support the shafts 4 on an inclined plane. Bearings 4' are provided for the shafts.

On each shaft 4 are disposed in close formation, a plurality of saws 5. These saws are of the regular gin saw type and between each saw is a spacer element 6, which, however, enables the saws to lie fairly close together, there being only a fractional space between the saws. The shafts 4 are made to revolve by a suitable pulley arrangement in the same direction as indicated by the arrows. Successive series of saws are close enough together to prevent any cotton seed from passing between the teeth, but are spaced far enough apart to permit the lint to pass through as it is combed and pulled from the seed.

Disposed between the top-most saws and the curvature of the casing 1 is a stripper of well known construction comprising a drum 7, upon which are arranged the angle irons or strips 8, the drum mounted on a shaft 9—all of well known construction. Below the stripper is a cotton seed conveyor 10. There are also provided roller brushes 11, disposed on the drums 12, the latter mounted on the shafts 13, for brushing or doffing the lint from the saws. The cotton lint is collected in the flues 14 and 15 and drawn into an air conduit 17, by means of air suction means, not shown.

The cotton is fed into the gin through the chute 18, feeder rolls 19 being disposed in the throat of the chute. Between the sloping wall of the casing 1 and the saws is arranged in spaced formation several spiked rollers 20. These rollers lie between adjacent saw series, and keep the cotton moving from one series of saws to the other.

In operation of the machine, cotton is fed into the chute 18, assisted by the feeder rolls 19, and falls upon the saws. One of the advantages of the gin saw arrangement as carried out in this invention is the increase in output by assembling a plurality of saws in series, and on an inclined plane. Where only two shafts of saws are used (as in former application referred to) the upper series of saws must revolve faster than those below.

In the present construction several series of saws are used, hence each higher saw series must revolve faster than the one preceding it. For instance, in the drawing in Figure 1, the lowermost saw series is rotated at say 100 R. P. M., the next saw series is turned at 200 R. P. M., the third series at 400 R. P. M. and the topmost series of saws are revolved at 800 R. P. M. In the order of the rotation, then, it will be clear that the cotton will, beginning at the second saw series from the bottom, be thrust outwardly toward the sloping wall of the casing in the direction of the rotation of the saws, faster than the cotton on the lowermost saws. This gives a combing, carding and pulling effect on the cotton in removing the seed therefrom. The same effect is had between the next two saw series, since each higher shaft carrying its complement of saws rotates at a higher rate of speed. The cotton is thus carried upwardly and kept moving in and out from the saws by the rollers 20. The lint removed from the seed is collected in the flues 14 and 15 and passes into the air suction conduit 17. The stripper carried on the shaft 9 strips the cotton seed from the uppermost saw series and the seed is deposited in the conveyor 10.

It is believed that the foregoing sufficiently explains the construction and operation of the gin and that further explanation will not be necessary. Obviously, the machine is capable of alterations and changes, such as will be within the scope and meaning of the following claims.

What is claimed as new is:

1. A ribless cotton gin, linter or delinter, comprising means for stripping cotton from the seed, said means consisting solely of co-acting ginning instrumentalities rotating in the same direction and spaced apart just sufficiently to permit passage of lint between the ginning instrumentalities, but without permitting passage of cotton seed, said ginning instrumentalities being mounted on parallel shafts whose axes are located in an inclined plane.
2. A ribless cotton gin, linter or delinter, comprising means for stripping cotton from the seed, said means consisting solely of co-acting ginning instrumentalities rotating in the same direction and spaced apart just sufficiently to permit passage of lint between the ginning instrumentalities, but without permitting passage of cotton seed, said ginning instrumentalities being mounted on parallel shafts whose axes are located in an inclined plane, the speeds of said rotating members increasing progressively from the lowermost to the uppermost members.
3. A ribless cotton gin, linter or delinter, comprising means for stripping cotton from the seed, said means consisting solely of co-acting ginning instrumentalities rotating in the same direction and spaced apart just suf-

ficiently to permit passage of lint between the ginning instrumentalities, but without permitting passage of cotton seed, said ginning instrumentalities being mounted on parallel shafts whose axes are located in an inclined plane, the speeds of said rotating members increasing progressively from the lowermost to the uppermost members, and means for supplying cotton to the lowermost of said rotating ginning members.

4. A ribless cotton gin, linter or delinter, comprising means for stripping cotton from the seed, said means consisting solely of co-acting ginning instrumentalities rotating in the same direction and spaced apart just sufficiently to permit passage of lint between the ginning instrumentalities, but without permitting passage of cotton seed, said ginning instrumentalities being mounted on parallel shafts whose axes are located in an inclined plane, the speeds of said rotating members increasing progressively from the lowermost to the uppermost members, means for supplying cotton to the lowermost of said rotating ginning members, and means for removing cotton seed adjacent the uppermost ginning member.

5. A ribless cotton gin, linter or delinter, comprising means for stripping cotton from the seed, said means consisting solely of co-acting ginning instrumentalities rotating in the same direction and spaced apart just sufficiently to permit passage of lint between the ginning instrumentalities, but without permitting passage of cotton seed, said ginning instrumentalities being mounted on parallel shafts whose axes are located in an inclined plane, the speeds of said rotating members increasing progressively from the lowermost to the uppermost members, means for supplying cotton to the lowermost of said rotating ginning members, and doffer rolls located below each pair of ginning instrumentalities for removing lint therefrom.

6. A ribless cotton gin, linter or delinter, comprising means for stripping cotton from the seed, said means consisting solely of co-acting ginning instrumentalities rotating in the same direction and spaced apart just sufficiently to permit passage of lint between the ginning instrumentalities, but without permitting passage of cotton seed, said ginning instrumentalities being mounted on parallel shafts whose axes are located in an inclined plane, the speeds of said rotating members increasingly progressively from the lowermost to the uppermost members, means for supplying cotton to the lowermost of said rotating ginning members, doffer rolls located below each pair of ginning instrumentalities for removing lint therefrom, and flues for conducting lint from each doffer roll.

7. A ribless cotton gin, linter or delinter, comprising means for stripping cotton from the seed, said means consisting solely of coact-

ing ginning instrumentalities rotating in the same direction and spaced apart just sufficiently to permit passage of lint between the ginning instrumentalities, but without permitting passage of cotton seed, said ginning instrumentalities being mounted on parallel shafts whose axes are located in an inclined plane, the speeds of said rotating members increasing progressively from the lowermost to the uppermost members, means for supplying cotton to the lowermost of said rotating ginning members, and auxiliary means for moving cotton successively from one rotating ginning member to another.

15 8. A ribless cotton gin, linter or delinter, comprising means for stripping cotton from the seed, said means consisting solely of coacting ginning instrumentalities rotating in the same direction and spaced apart just sufficiently to permit passage of lint between the ginning instrumentalities, but without permitting passage of cotton seed, said ginning instrumentalities being mounted on parallel shafts whose axes are located in an inclined plane, the speeds of said rotating members increasing progressively from the lowermost to the uppermost members, means for supplying cotton to the lowermost of said rotating ginning members, and auxiliary means for moving cotton successively from one rotating ginning member to another, said auxiliary means comprising spiked rollers serving also for rotating and agitating the cotton in passing from one ginning member to another.

35 9. A ribless cotton gin, linter or delinter, comprising means for stripping cotton from the seed, said means consisting solely of a series of coacting ginning instrumentalities rotating in the same direction about parallel axes, adjacent members of the series being spaced apart from each other so as not to intersect a plane placed between them and spaced just sufficiently to permit passage of lint between them, but without permitting

45 passage of cotton seed.

10. A ribless cotton gin, linter or delinter, comprising means for stripping cotton from the seed, said means consisting solely of a series of coacting ginning instrumentalities 50 rotating in the same direction about parallel axes, adjacent members of the series being spaced apart from each other just sufficiently to permit passage of lint between them, but without permitting passage of cotton seed, and means for supplying cotton to the ginning instrumentalities adjacent one end of the series.

11. A ribless cotton gin, linter or delinter, comprising means for stripping cotton from the seed, said means consisting solely of a series of coacting ginning instrumentalities 55 rotating in the same direction about parallel axes, adjacent members of a series being spaced apart from each other just sufficiently to permit passage of lint between them, but

without permitting passage of cotton seed, means for supplying cotton to the ginning instrumentalities adjacent one end of the series, and means for removing cotton seed at the other end of the series.

12. A ribless cotton gin, linter or delinter, comprising means for stripping cotton from the seed, said means consisting solely of a series of coacting ginning instrumentalities 60 rotating in the same direction about parallel axes, adjacent members of a series being spaced apart from each other just sufficiently to permit passage of lint between them, but without permitting passage of cotton seed, means for supplying cotton to the ginning instrumentalities adjacent one end of the series, and means for removing cotton seed at the other end of the series, said means comprising a stripper roll, and a seed conveyor located below said stripper roll.

13. A ribless cotton gin, linter or delinter, comprising means for stripping cotton from the seed, said means consisting solely of a series of pairs of coacting ginning instrumentalities 65 rotating in the same direction about parallel axes and spaced apart just sufficiently to permit passage of lint between the ginning instrumentalities, but without permitting passage of cotton seed, and doffer rolls, one located below each pair of ginning instrumentalities, for removing lint therefrom.

14. A ribless cotton gin, linter or delinter, comprising means for stripping cotton from the seed, said means consisting solely of a series of pairs of coacting ginning instrumentalities 70 rotating in the same direction about parallel axes and spaced apart just sufficiently to permit passage of lint between the ginning instrumentalities, but without permitting passage of cotton seed, means for supplying cotton to the ginning instrumentalities adjacent one end of the series, and means for removing cotton seed at the other end of the series, said means comprising a stripper roll, a seed conveyor located below 75 said stripper roll, and doffer rolls, one located below each pair of ginning instrumentalities, for removing lint therefrom.

15. A ribless cotton gin, linter or delinter, comprising means for stripping cotton from the seed, said means consisting solely of a series of pairs of coacting ginning instrumentalities 80 rotating in the same direction about parallel axes and spaced apart just sufficiently to permit passage of lint between the ginning instrumentalities, but without permitting passage of cotton seed, and spiked rollers, one located adjacent each pair of ginning instrumentalities, for advancing cotton 85 from one ginning instrumentality to another.

In testimony whereof I affix my signature.
FREDERICK B. CUMPSTON.
